UNITED STATES PATENT OFFICE.

CARL FERRARI, OF ERIE, PENNSYLVANIA, ASSIGNOR TO ERIE CITY IRON WORKS, OF ERIE, PENNSYLVANIA, A CORPORATION OF PENNSYLVANIA.

STEAM-ENGINE.

No. 896,524.

Specification of Letters Patent. Patented Aug. 18, 1908.

Application filed August 8, 1907. Serial No. 387,583.

To all whom it may concern:

Be it known that I, CARL FERRARI, a citizen of the United States, residing at Erie, in the county of Erie and State of Pennsylvania, have invented new and useful Improvements in Steam-Engines, of which the following is a specification.

This invention relates to steam engines and consists in certain improvements in the construction thereof as will be hereinafter 10 fully described and pointed out in the claims.

One of the objects of the invention is to provide a valve mechanism by means of 15 which a uniform pressure may be maintained in the cylinder until the point of cut-off and to reduce the clearance and simplify the mechanism for accomplishing this purpose.

20 The invention is illustrated in the accompanying drawings as follows:

Figure 1 shows a section on the line 1—1 in Fig. 2. Fig. 2 shows a section on the line 2—2 in Fig. 1. Fig. 3 shows a plan view of 25 the valve. Fig. 4 shows a side elevation of the same. Fig. 5 shows an end elevation of the same. Fig. 6 shows a bottom view of the pressure plate. Fig. 7 shows an end view partly in section on the line 7—7 in Fig. 6. Fig. 8 shows an end view partly in section on the line 8—8 in Fig. 6. Fig. 9 shows a longitudinal section through the valve and steam chest with the valve at the point of opening. Fig. 10. shows a similar 30 view with the valve slightly advanced. Fig. 35 11 a view showing the valve moved to a position with nearly full opening.

1 marks the cylinder; 2 the piston; 3 the steam chest. The main ports 4 connect the 40 steam chest with the cylinder 1: auxiliary ports 5 extend from the valve seat in the steam chest and lead into the main ports 4. In this way clearance, incident to the auxiliary ports, may be quite materially reduced. 45 The valve is formed of two parts 6, connected by the rods 7 and operate on the seat in the steam chest over the ports 4 and 5, and under a pressure plate 8.

The valve has the steam edges 10, 11 and 50 12 which are brought into play as steam is admitted. These edges operate in connection with the steam edges 10^a, 11^a and 12^a in the valve seat in the steam chest and with the steam edges 10^b, 11^b and 12^b in the 55 pressure plates, as clearly shown in Fig. 9.

Each pressure plate is provided with a cavity 8^a of the same area as the port 4 and arranged opposite to said port. It is also provided with a cavity 8^c of equal area to the auxiliary port 5 and this is arranged 60 opposite to the auxiliary port. The pressure plate also has a passage 8^b extending through it, separating the pressure plate into two parts 8^d and 8^e which are connected by the bridge pieces 8^f.

It will be noted that steam passes to the main port (as indicated in Fig. 10) both by way of the end of the valve and through the passage 8^b. In order to deliver steam by the edge 11^a, a passage 6^b is arranged in the valve 70 so that steam passes through it from the passage 8^b and into the cavity 13 and this is opposite to the passage 8^b and of equal area. The valve also has a passage 6^a so that the steam passing by the steam edges 10^b and 11^b 75 moves through the passage 6^a to the main port. Steam is delivered to the auxiliary port by the steam edge 12^a, through the cavity 13 as well as directly. In order that the steam passing the edge 12^b may enter the 80 auxiliary port, a passage 6^c is provided in the valve and this carries the steam passing the edge 12^b and cavity 8^c to the auxiliary port. In this way, steam is delivered from both 85 sides of the main port and from four points of opening, while steam is delivered to the auxiliary port only from one side and from two points of opening, so that in all there are six points of opening. All these openings are effective in the initial movement of the valve 90 so that a full quota of steam is delivered to the cylinder with the initial opening. The auxiliary port remains open until the opening for the main port is of such dimensions as to maintain full pressure in the cylinder. 95 This, of course, means that the steam velocity through the ports remains practically constant. As soon as the main port is sufficiently opened, the auxiliary port is closed, as shown in Fig. 11 and remains closed until 100 toward the end of the opening of the main port. The steam edges 14 on the valve and edge 14^a on the valve seat and 14^b on the pressure plate effect this closure. It is then again opened on the return movement of the valve so as to maintain full portage during the cut-off movement and is closed simultaneously with the main port. A separate valve (not shown) controls the exhaust. The 105 valve has the extensions 6^d which maintain 110

a closure of the sides of the auxiliary ports toward the center of the valve at all times. By this means I am enabled to maintain a practical uniformity of steam pressure in the cylinder during the opening of the ports and in consequence, to permit a uniformity of velocity of steam through the ports; and in doing this the variation of piston speed is considered.

10 The pressure plates are adjusted by means of the set screws 15. These set screws abut against the walls 16 of the openings 17. The steam chest is perfectly formed with a bridge 18 extending over the central part of the valve so that the openings necessary to cover are only at the ends of the steam chest and directly over the valve seats. These openings are closed by the covers 20. The pressure plates are maintained in position to seat 20 the valve by the springs 19.

What I claim as new is:

1. In a steam engine the combination of a cylinder; a steam chest having main admission ports and auxiliary ports; and a valve 25 arranged to deliver steam to the main ports from both sides of the main ports and with four points of admission for each of said main ports and to the auxiliary ports with two points of admission.

30 2. In a steam engine the combination of a cylinder; a steam chest having main admission ports and auxiliary ports; and a valve arranged to deliver steam to the main ports from both sides of the main ports and with 35 four points of admission for each of said main ports and to the auxiliary ports with two points of admission and from one side only of the auxiliary port.

3. In a steam engine the combination of a 40 cylinder; a steam chest having a main admission port and an auxiliary port; a pressure plate having an opening through it intermediate its ends; and a valve adapted to operate with said ports and pressure plate to deliver steam to the main port from both sides of the main port, one side being through the opening in the pressure plate and to deliver steam to the auxiliary port from one side and through the opening in the pressure plate.

45 4. In a steam engine the combination of a cylinder; a steam chest having a main admission port and an auxiliary port; a pressure plate having an opening through it intermediate its ends and cavities arranged in 50 register with said ports; and a valve adapted to operate with said ports and pressure plate to deliver steam to the main port from both sides of the main port and with four points of admission, two of which are through the 55 opening in the pressure plate, and to deliver steam to the auxiliary port from one side and with two points of admission.

60 5. In a steam engine the combination of a cylinder; a steam chest having a main admission port and an auxiliary port and steam

cavity 13; a pressure plate having a passage 8^b through it in register with cavity 13, cavities 8^a and 8^c opposite the main and auxiliary ports respectively; and a valve having the steam edges 10, 11 and 12, the edge 10 70 being adapted to operate with the main port and cavity 8^a, the edge 11 with the passage 8^b and cavity 13, and the edge 12 with the auxiliary port and cavity 8^c.

6. In a steam engine the combination of a 75 cylinder; a steam chest having a main port and an auxiliary port and steam cavity 13; a pressure plate having a passage 8^b through it in register with cavity 13, and cavities 8^a and 8^c opposite the main and auxiliary ports respectively; and a valve having the steam edges 10, 11 and 12, the edge 10 being adapted to operate with the main port and cavity 8^a; the edge 11 with the passage 8^b and cavity 13, and the edge 12 with the auxiliary 80 port and cavity 8^c, said valve being provided with passages 6^a 6^b and 6^c for the purposes described.

7. In a steam engine the combination of a 90 cylinder; a steam chest having a main admission port and an auxiliary port and steam cavity 13; a pressure plate having a passage 8^b through it in register with cavity 13, and cavities 8^a and 8^c opposite the main and auxiliary ports respectively; and a valve having 95 the steam edges 10, 11 and 12, the edge 10 being adapted to operate with the main port and cavity 8^a; the edge 11 with the passage 8^b and cavity 13, and the edge 12 with the auxiliary port and cavity 8^c; the valve having the extended end 6^d to maintain a closure 100 on one side of the auxiliary port.

8. In a steam engine the combination of a cylinder; a steam chest having main and auxiliary ports and pressure plate; a valve 105 operating under the pressure plate and in connection with said ports, said valve having the extended end 6^d for the purpose described.

9. In a steam engine the combination of a 110 cylinder; a steam chest having a main admission port and auxiliary admission port; and a valve adapted to open the auxiliary port during the early part of the opening of the main port and to close the auxiliary port 115 during the intermediate part of the opening of the main port.

10. In a steam engine the combination of a cylinder; a steam chest having a main admission port and auxiliary admission port; 120 and a valve adapted to open the auxiliary port during the early part of the opening of the main port and to close the auxiliary port during the intermediate part of the opening of the main port, and then to open the auxiliary port during the latter part of the opening of the main port.

11. In a steam engine the combination of a cylinder; a steam chest having a main admission port and auxiliary admission port; 125

and a valve adapted to open the auxiliary port during the latter part of the opening of the main port and to close the auxiliary port during the intermediate part of the opening 5 of the main port.

12. In a steam engine the combination of a cylinder; a steam chest having a main admission port and an auxiliary admission port; and a valve adapted to open the auxiliary 10 port with the initial opening of the main port and to close the auxiliary port during the intermediate part of the opening of the main port.

13. In a steam engine the combination of 15 a cylinder; a steam chest having a main admission port and an auxiliary admission port; and a valve adapted to open the auxiliary port during the latter part of the opening of the main port and to close the 20 same coincident with the closing of the main port.

14. In a steam engine the combination of 25 a cylinder; a steam chest having a main admission port and an auxiliary port leading from the steam chest into the main port; and a valve adapted to open the auxiliary port during the early part of the opening of the main port and to close the auxiliary port during the intermediate part of the opening 30 of the main port.

15. In a steam engine the combination of 35 a cylinder; a steam chest having a main admission port and an auxiliary port; and a valve arranged to deliver steam to the main port from both sides of the main port and with four points of admission, and to open the auxiliary port during the early part of the opening of the main port and to close the auxiliary port during the intermediate 40 part of the opening of the main port.

16. In a steam engine the combination of the cylinder; the steam chest having the main admission port and an auxiliary port; and a valve arranged to deliver steam to the

main port from both sides of the main port 45 and with four points of admission and to the auxiliary port from two points of admission from one side, and to open the auxiliary port during the early part of the opening of the main port and to close the auxiliary port 50 during the intermediate part of the opening of the main port.

17. In a steam engine the combination of the cylinder; the steam chest having a main and an auxiliary port; the pressure plate 55 having an opening through it intermediate its ends; and a valve adapted to operate with said ports and pressure plate and to deliver steam to both sides of the main port, one side being through the opening in the plate; and to deliver steam to the auxiliary port from one side of said auxiliary port and through the opening in the pressure plate, and adapted to open the auxiliary port during the early part of the opening of the main port 60 and to close the auxiliary port during the intermediate part of the opening of the main port and then again to open the auxiliary port during the latter part of the opening of the main port. 70

18. In a steam engine the combination with the cylinder; the steam chest having a main and an auxiliary port at each end thereof; pressure plates comprising the parts 8^d over the main ports and 8^e over the 75 auxiliary ports, said parts 8^d and 8^e being connected and having passages 8^b between them for carrying steam to the ports; and a valve operating with relation to the ports and pressure plates. 80

In testimony whereof I have hereunto set my hand in the presence of two subscribing witnesses.

CARL FERRARI.
